Primary Examiner — Ricky Pham(74) *Attorney, Agent, or Firm* — Birch, Stewart, Kolasch & Birch, LLP(57) **CLAIM**

The ornamental design for an instant noodle holder, as shown and described.

DESCRIPTION

FIG. 1 is a top perspective view of the instant noodle holder, shown without a cover for ease of illustration;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is a bottom view thereof; and,

FIG. 8 is a top perspective view of the instant noodle holder with a cover in place on the top of the instant noodle holder. The broken lines shown in the drawings are for illustrative purposes only and form no part of the claimed design.
